United States Patent Office.

ROBERT BAIN, OF BROOKLYN, NEW YORK.

Letters Patent No. 63,689, dated April 9, 1867.

IMPROVEMENT IN PIPE WRENCH.

The Schedule referred to in these Letters Patent and making part of the same.

TO ALL WHOM IT MAY CONCERN:

Be it known that I, ROBERT BAIN, of Brooklyn, in the county of Kings, and State of New York, have invented a certain new and useful Improvement in Pipe Wrenches or Tongs, of which the following is a full, clear, and exact description, reference being had to the accompanying drawing, forming part of this specification, and in which—

Figure 1 represents a side view of a pipe wrench constructed according to my improvement, having a pipe in its grip or hold.

Figure 2, a back edge view of the same tool.

Figure 3, a transverse sectional view through the line xx in fig. 1; and

Figure 4, an interior side view of the fixed jaw detached with its handle or lever.

Like letters indicate like parts throughout the several figures.

The nature of my invention consists in combination, with a fixed jaw and adjustably pivoted claw or jaw extended to form handles or levers, of a sliding strap and set or locking-screw arranged to pass through the claw and inner side of the strap, into a female thread of which it fits, and through which when screwed down it projects and enters any one of a series of countersinks or female centres made in the inner side of the jaw on which the strap slides, said strap forming the pivoted attachment on which the claw or movable jaw works, and is connected with, (so as to admit of its ready detachment or adjustment,) a wedge or gib being preferably provided the sliding strap within its outer side or face, to secure the connection of the two jaws when established, and to relieve the screw from strain.

Referring to the accompanying drawing, A represents the fixed jaw, and B the movable one or claw, extended to form levers or handles, constituting what may be termed jaw-levers. The fixed jaw A is provided on its inner side or face with a series of countersinks or female centres, a , corresponding to the required adjustment of the wrench to suit a variety of sizes of pipe. Said jaw may also have on one of its outer edges or faces gauge marks, b , to indicate the proper position of the movable jaw or its sliding attachment for a given adjustment. On this stationary jaw A is arranged a sliding strap, C, to the one side of which is pivoted the adjustable jaw or claw B, being locked thereon by means of a removable set-screw, D, so that said claw may readily be adjusted or detached at pleasure. This screw D, while it secures in the place of a fixed rivet, the pivoted attachment of the movable jaw or claw, need not necessarily, or directly rather, be the pivot, in the strict sense of the term, on which said jaws turns, as the sliding strap C may be provided with a projecting socket, e, that forms a bearing or fulcrum to the movable jaw, and through which the screw D fits and works or screws. This pivoted attachment of the jaw to the slide adds materially to the strength of the tool as compared with making the screw directly the pivot. The point of the screw D enters, when the adjustment is established, either one of a series of countersinks, a , which determines the proper position of the sliding strap C for a given adjustment, and that may readily be decided by gauge marks b , on the back edge of the jaw A, and adjusting the sliding strap relatively thereto so as to bring the point of the slackened screw over the particular countersink for a certain adjustment of the wrench. To relieve the screw D of strain, after the adjustment has been made, and to tighten up the connection of the sliding attachment to the adjustable jaw, a wedge or bevel-faced gib, F, is fitted in between the strap and stationary jaw on the side opposite to the screw. This gib, on being slightly tapped or driven up, not only secures the connection and relieves the screw, but gives a firm and stable character to the wrench and scarcely or at all interferes with the adjustment or detachment of the movable jaw, as a single tap on the one end of such gib frees it from lock on the strap, when the screw D may be slackened and the claw be adjusted or removed at pleasure. By dispensing with a fixed rivet as a pivot to the movable jaw, the latter can be readily detached to facilitate re-sharpening or setting of its claw end or to replace it by another in case of fractures, or replacement of the sliding straps or other portion.

What I claim as my invention, and desire to secure by Letters Patent, is—

In combination with the jaw levers A and B, the sliding strap C, with its screw D, and wedge or gib F, for operation together essentially as herein set forth.

ROBERT BAIN.
